WHEEL HUB CAP

Arthur Ross, Detroit, Mich., assignor to General
Motors Corporation, Detroit, Mich., a corpora-
tion of Delaware

Application November 12, 1949, Serial No. 6,000

Term of patent 7 years

(Cl. D14—30)

To all whom it may concern:

Be it known that I, Arthur Ross, a citizen of the United States, being a resident of Detroit, State of Michigan, have invented a new, original, and ornamental Design for a Wheel Hub Cap, of which the following is a specification, reference being made to the accompanying drawing, forming a part thereof.

In the drawing:

Figure 1 is a plan view of a wheel hub cap embodying my new design.

Figure 2 is a side elevation thereof.

Figure 3 is a sectional view taken substantially on line 3—3 of Figure 1.

The characteristic features of my design re-

side in the parts shown by means of full lines in the drawing.

I claim:

The ornamental design for a wheel hub cap, substantially as shown and described.

ARTHUR ROSS.
